(57) CLAIM

The ornamental design for a portion of a shoe upper, as shown and described.

DESCRIPTION

FIG. 1 is a front perspective view of a portion of a shoe upper showing my new design;

FIG. 2 is a side view thereof;

FIG. 3 is a top view thereof;

FIG. 4 is a front view thereof;

FIG. 5 is a rear perspective view thereof; and,

FIG. 6 is a rear view thereof.

The solid line immediately adjacent to the shaded area at the right side of the shaded area represents a claimed boundary of the design. The uneven broken lines immediately adjacent to the shaded area represent unclaimed boundaries of the design. The uneven broken line showing of the various oval shapes and the eyelet in the shaded region and the remainder of the shoe is for illustrative purposes only and forms no part of the claimed design.
